HAND SPOOLING APPARATUS

Peter Georg Grove Beyer, Copenhagen, Denmark

Application October 18, 1934, Serial No. 748,954
In Denmark October 18, 1933

1 Claim. (Cl. 242—2)

This invention relates to a hand spooling apparatus which pulls out the yarn from the hanks or skeins stretched on a vertically revolving reel and winds it up under a slight tension into a ball of windings laid crosswise and very near to the ball's axis, in order that the windings may not slip off and thus cause entanglement of the yarn.

The figure shows a side elevation of the apparatus.

1 is a base to which is fastened a support 2 of flat iron provided with a pivot 3, on which is turned a spindle 4 having a socket 5 in which a ball 6 and spiral spring 7 are seated; the spindle carries a friction disc 8 and a tubular spool 10 with a hook 9.

An inclined shaft 11 having attached a rubber roller 12 is journaled in the support 2 and carries a crank wheel 13 with handle 14, revolving movement being transmitted to a perforated wheel 15 with rubber tire and also to a winding arm 16 made of metal wire that has been shaped into eyelets 17 and 18.

The yarn hanks are hung on some reel (not shown) and from there the yarn end is brought down and passed through the wheel 15, the eyelets 17 and 18, and finally it is fastened to the hook 9.

By turning the crank wheel 13 the yarn will be unwound from the reel and wound around the spool 10 into a ball with crossed windings.

When, for example, five hanks or skeins have been wound into a ball, it is slid off the spool 10, whereby the end of the yarn inside of the ball is being pulled out, and thereupon it is unhooked.

The hand spooling apparatus may be fastened by a screw 22 to a handle, not shown, instead of to the base 1.

What I claim is:

Spooling apparatus, comprising a frame having a horizontal portion and an inclined portion, a vertical spindle adapted to rotate on the horizontal portion of the frame, a winding wheel adapted to rotate on the inclined portion of the frame, the axis of the winding wheel being perpendicular to the inclined portion of the frame, a winding arm attached to the winding wheel and extending over the spindle, the winding wheel being apertured to permit the material to pass therethrough and onto the winding arm, and means for simultaneously rotating the spindle and the wheel, comprising a crank wheel in contact with the winding wheel, whereby the material is wound on the spindle in a criss-cross manner to produce a ball of oblong cross-section, the inclined portion of the frame making a very large acute angle with the horizontal portion, whereby the windings are laid as nearly parallel to the axis of the spindle as the passage of the winding arm about the spindle will allow.

PETER GEORG GROVE BEYER.
